UNITED STATES PATENT OFFICE.

JOHN M. MARTY, OF CLEVELAND, OHIO, ASSIGNOR OF ONE-HALF TO
CHARLES J. DIEBOLD, OF CLEVELAND, OHIO.

MINE-GATE.

SPECIFICATION forming part of Letters Patent No. 718,138, dated January 13, 1903.

Application filed September 10, 1902. Serial No. 122,812. (No model.)

To all whom it may concern:

Be it known that I, JOHN M. MARTY, a citizen of the United States, residing in Cleveland, county of Cuyahoga, and State of Ohio, have invented certain new and useful Improvements in Mine-Gates; and I do hereby declare the following to be a full, clear, and exact description of my invention, such as will enable others skilled in the art to which it appertains to make and use the same.

My invention relates to improvements in gates for mines, such as are adapted to cut off or control currents of air in tunnels and are automatically opened and closed as the car approaches or leaves the gate. The gate I have adopted is of the folding type; and the object of my invention is to provide a simple and efficient mechanism for raising and lowering it. I accomplish this by providing an additional rail and raising it above the track-rail a sufficient distance on either side of the gate and holding it in the raised position so long as it is desired to keep the gate lowered. This additional rail is held in its raised position by means of weights and levers, the weights being of such size that the weight of the car will by overbalancing the weights lower the secondary rail and raise the gate, as hereinafter more fully described.

In the accompanying drawings, Figure 1 is a side elevation showing the curtain lowered. Fig. 2 is an end view at line $x-x$ in Fig. 1. Fig. 3 is a side elevation of one end, showing the position of the parts when the curtain is raised. Fig. 4 is a plan view of the part shown in Fig. 3.

A A are the usual track-rails. C and C² are rails mounted above one of the rails A and pivotally connected to the short sections of rail C' C³. These rails are herein referred to as "secondary" rails. The outer ends of the secondary rails C' and C³ are pivotally connected to the lugs a, which are rigidly fastened to the track-rail A.

D and D' are weighted levers pivoted at d⁴ and d⁵ and are provided with arms d d' d² d³. The arm d' of the lever D is connected to the rails C and C' at the point where the rails are united by the connecting-link c, and the arm d³ is connected to the rails C² C³ at their junction by the connecting-link c'. The weights

on the ends of the levers D D' are sufficiently heavy to raise the secondary rails above the track-rail, except when the weight of the car is upon them, as indicated by dotted lines in Fig. 3.

B, B', and B² are posts of a frame for supporting the curtain and the parts upon which it is mounted.

b and b' are vertical iron bars extending from the lower part of the frame to the top of the posts B' B², as shown in Fig. 3.

Near the top of the post B² are mounted the segments K and L, the teeth of which mesh, also shown in Fig. 3. The arm d of the lever D is connected to the segment K by means of the rod G, Figs. 1 and 3. The arm d of the lever D is also connected through the connecting-rod E to the lever F, which is pivoted at f. The rod H connects the lower end of the arm F to the arm of the segment L. The rods I and J connect the pivoted levers F and F', so that the secondary rails on both sides of the gate will be lowered and the curtain raised as the car approaches from either side. It would be practicable to make the rods G and I of sufficient strength to either raise or lower the curtain; but I prefer to use two rods of lighter weight, which I am able to do by alternate pulling on the segments K and L. The guides c² c³ fit into the corresponding parts a² a' to prevent lateral motion of the secondary rail.

O is a folding curtain mounted between two sets of so-called "lazy-tongs," the upper section of each set being attached to the upper pole of the curtain, while the lower section of each set is attached to the lower pole of the curtain. The lower pole of the curtain slides up and down between the posts B' B² and the bars b' and b as the lazy-tongs are extended or drawn together. On the inner side of the segment K is an arm M, Figs. 2 and 4, the outer end of which is connected to the upper section of the lazy-tongs P.

The rod M² passes through the upper end of the frame and is provided at the opposite end with the arm M', the outer end of which is connected to the upper section of the lazy-tongs P', both the arms M and M' being rigidly fastened to the rod M².

It will be understood that when the weight

of the car is not present on the secondary rails the weights on the ends of the levers D D' will raise these rails, and as the arm d of the lever D is raised by the descending weight it will, through the connecting-rods, turn the segments K and L, so as to lower the curtain by extending the lazy-tongs on either side of it. This is the normal position of the apparatus until as the car approaches from either end its weight comes upon the secondary rail and forces it downward against the power of the weighted levers and through the parts connected thereto contracts the lazy-tongs, raising the curtain. The curtain remains raised until the car has passed off the secondary rail at the other side of the gate. As the car leaves the secondary rail the weighted levers again raise the rail and through the operative connection with the curtain lower it. The rails C and C² overlap each other, and the weight of the car as it passes through the gate produces sufficient friction between them to prevent the weighted levers from lowering the curtain.

25 When it is desired to use the gate on a curve, I connect to the rods J and I the links j j', pivotally secured to the track, as shown in rod J, Figs. 1 and 4.

Having described my invention, I claim—

- 30 1. In a mine-gate, the combination with the track-rail of a secondary rail mounted above the track-rail, a weighted lever connected with the secondary rail, a folding curtain mounted between lazy-tongs supported in a frame, and rods connecting said lazy-tongs with said secondary rail and weighted lever, whereby the weight of the approaching car will raise the curtain and the weighted lever
- 35

will lower the curtain as the car is removed, substantially as set forth. 40

2. In a mine-gate, the combination with the track-rail, of secondary rails on each side of the gate, weighted levers attached to the secondary rails, a curtain mounted in a frame and operated by a pair of lazy-tongs, and rods 45 for connecting the secondary rails and weighted lever to the lazy-tongs, whereby the curtain is raised as the car approaches the gate and is lowered as the car leaves the gate, substantially as shown and described. 50

3. In a mine-gate, the combination with the track-rail A of the secondary rails C, C', the weighted lever D, the curtain O, the lazy-tongs P P', the arms M, M' mounted on the rod M², the segments K and L, the lever F 55 and the connecting-rods G, E and H, all for raising the curtain as the car approaches the gate and lowering the gate as the car is removed therefrom, substantially as and for the purpose specified. 60

4. In a mine-gate, the combination with the track-rail A of the secondary rails C, C', C² and C³, the levers D and D', the curtain O, the lazy-tongs P, P', the arms M, M', the rod M², the segments K and L, the levers F and F', and the rods E, G, H, I and J, all substantially as and for the purpose specified. 65

In testimony whereof I hereunto set my hand, at Cleveland, Ohio, in the presence of two witnesses, this 5th day of September, 70 1902.

JOHN M. MARTY.
